UNITED STATES PATENT OFFICE.

CHARLES E. CHADDOCK AND RICHARD G. CHADDOCK, OF CANTON, OHIO.

GLOVE.

964,608.

Specification of Letters Patent. Patented July 19, 1910.

Application filed September 2, 1909. Serial No. 515,811.

To all whom it may concern:

Be it known that we, CHARLES E. CHADDOCK and RICHARD G. CHADDOCK, citizens of the United States, both residing at Canton, 5 in the county of Stark and State of Ohio, have invented certain new and useful Improvements in Gloves, of which the following is a specification:

This invention relates to gloves and refers 10 particularly to an improved construction of a glove which is especially adapted for usage in hard work.

An object of this invention is to form a glove by the employment of two dies or by 15 two separate stamps, one die being for the body portion of the glove while the second die is for the thumb piece which is used in connection with the half-fourchette formed integrally with the body of the glove.

20 It is well-known that in the glove art the opposite sides of gloves have been provided with padding to increase their efficiency in retaining the warmth of the hand as well as to protect the hand from chafing 25 when working. It is also well-known that the padding is easily displaced incident to the use of the glove and that the same wabbles and creases whereby an uneven gripping surface is the result as well as leaving certain portions of the hand unprotected.

One of the objects of this invention is to 30 overcome this objection by forming a padding or thickness to the opposite sides of the glove that is rigid with respect to the glove and that cannot be displaced by creasing the glove or by any rubbing action against the opposite sides of the same. This object is effected by a peculiar shirring which 35 will be hereinafter specifically set forth. Furthermore, it is known that a tight fitting glove gives but little warmth, and that a loose fitting glove cannot be conveniently worn when working.

40 This invention aims to provide a glove which overcomes these disadvantages by forming a glove which conforms to the hand and in which are positioned pockets or air chambers to admit a film of air to accumulate between the hand and the side of the glove which is heated by the hand, and which thus affords a greater protection against the cold for the hand.

In conjunction with these objects, the invention provides a glove with a shirred portion so arranged as to form gripping sur-

faces, whereby a firm hold may be had upon various tools and implements handled by the workman when wearing the improved glove.

The invention has for a further object the utilizing of the excess material in the body portion and in the central portion of the same which covers the palm of the hand, by reinforcing the glove in such a manner 65 as to provide a shirred portion in the palms which also protects the hands of the wearer.

The invention has for a still further object the provision of a glove which possesses the above enumerated advantages and which 70 may be applied to either the left or the right hand, the shirred portion of the same forming the glove which fits snugly to the hand and enables the free movement of the hand.

For a full understanding of the invention 75 reference is to be had to the following description and accompanying drawings, in which:

Figure 1 is a perspective view of the complete glove, Fig. 2 is a section on the line 80 2-2 of Fig. 1, and Fig. 3 is a plan view of the blanks after being cut.

Corresponding and like parts are referred to in the following description and indicated in all the views of the drawings by 85 the same reference characters.

Referring specifically to the drawings, the numeral 10 designates the main blank of the glove which is so stamped as to provide a plurality of half-fingers 11 along one of the 90 longitudinal edges of the blank which are formed of such a length as to correspond with one another upon the overlapping of the blank and to accommodate the respective fingers of the wearer. In the opposite 95 edge of the blank 10 a half-fourchette 12 is formed to support a thumb piece 13 which is stitched about the edges of the same and also about the edges of the blank 10 from which the half-fourchette 12 is cut.

100 In forming the glove the blank 10 is overlapped upon itself and sewed at its outer side as at 14 to secure the adjacent edges of the blank 10. The half-fingers 11 are likewise stitched at their adjacent edges to 105 form the fingers of the glove as disclosed in Fig. 2. It will be noted that when the glove is thus formed the palm of the same will be of a width greater than that of the hand of the wearer and for the purpose of reducing the width of the glove the palms of the same are shirred or gathered, as is disclosed.

at 15, to take up such width. In this formation it is noted that the palm of the glove will be strengthened by the fullness of the material and will give additional wear to the glove at the point where the greatest friction is had upon the same. The glove thus formed may also be utilized for the purpose of protecting the hands of the wearer in working or otherwise, by reason 10 of the stirring.

A wristband 16 is employed which is secured to the inner edge of the glove in the usual manner and may be formed of a sufficient size to accommodate the blank 10 after 15 the stirring of the same.

Having thus described the invention, what is claimed as new is:

1. In a glove, the combination of a blank adapted to be folded upon itself, and having 20 a plurality of fingers formed along one edge of the same, a half fourchette stamped from

the opposite edge of the blank, and a thumb-piece stitched about said half fourchette and about the adjacent edges of said blank, said blank being stirred at its opposite sides to 25 present a reinforced palm and back to the glove for the protection of the wearer.

2. A glove having stirred opposite sides to form roughened gripping surfaces, said stirred sides also forming air pockets to 30 admit a film of air between the glove and the hand, said stirred sides providing reinforcements for the protection of the hand in gripping an object.

In testimony whereof we affix our signatures in presence of two witnesses.

CHARLES E. CHADDOCK. [L.S.]
RICHARD G. CHADDOCK. [L.S.]
